UNITED STATES PATENT OFFICE

99,147

DESIGN FOR A TOY FIGURE

Adelaide M. Tweed, Wickenburg, Ariz., assignor to Ruth D. Tweed, Wickenburg, Ariz.

Application September 13, 1935, Serial No. 58,541

Term of patent 3½ years

To whom it may concern:

Be it known that I, Adelaide M. Tweed, a citizen of the United States, residing at Wickenburg, in the county of Maricopa and State of Arizona, have invented a new, original, and ornamental Design for a Toy Figure, of which the following is a specification, reference being had to the accompanying drawing, forming a part thereof.

Fig. 1 is a front view of a toy figure, showing my new design; and

Fig. 2 is a side view thereof.

I claim:

The ornamental design for a toy figure, as shown.

ADELAIDE M. TWEED.
